Primary Examiner — T. Chase Nelson*Assistant Examiner* — Kathleen M Sims(74) *Attorney, Agent, or Firm* — Alston & Bird LLP(57) **CLAIM**

We claim the ornamental design for a dishwasher spray arm, as shown and described.

DESCRIPTION

FIG. 1 is a perspective view of a dishwasher spray arm showing our new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is an exploded perspective view thereof;

FIG. 9 is an exploded top view thereof;

FIG. 10 is an exploded bottom view thereof; and,

FIG. 11 is an exploded front view thereof. The broken lines are directed to environment and are for illustrative purposes only. The broken lines form no part of the claimed design.
